UNITED STATES PATENT OFFICE.

GUSTAVE FERNEKES, OF PITTSBURGH, PENNSYLVANIA, ASSIGNOR TO JOHN A. SNEE,
OF WEST ELIZABETH, PENNSYLVANIA.

APPARATUS FOR PRODUCING FORMALDEHYDE.

1,038,546.

Specification of Letters Patent. Patented Sept. 17, 1912.

Application filed February 18, 1911. Serial No. 609,480.

To all whom it may concern:

Be it known that I, GUSTAVE FERNEKES, a resident of Pittsburgh, in the county of Allegheny and State of Pennsylvania, have 5 invented certain new and useful Improvements in Apparatus for Producing Formaldehyde, of which the following is a specification.

This invention relates primarily to the 10 production of formaldehyde by the oxidation of methane, though it has reference to the production and utilization of such other substances as are incident to the production of formaldehyde. The invention is not restricted as regards the source of the methane, as it contemplates the oxidation of methane from whatever source which results in its conversion into formaldehyde, the latter being collected preferably by a 15 process of absorption. The mode which I have adopted for effecting this oxidation consists in causing such an incomplete burning of a combustible gas containing methane as will result in the desired oxidation.

20 Natural gas is produced in various parts of the country which contains methane in quantities sufficient to produce formaldehyde on a commercial scale by means of my invention, and it is to the utilization of such 25 gas that the invention is especially directed, though as above indicated, not necessarily restricted. Formic acid and carbon dioxid are produced in addition to formaldehyde, and a further purpose of the invention is to 30 separate these substances and to provide for 35 the utilization of the carbon dioxid.

A special form of combustion chamber is utilized for practising the invention in its preferred adaptation, the chamber being so 40 inclosed as to enable me to control the combustion in such manner as to obtain the products, to which reference has been made, by a process of partial or incomplete combustion.

45 In the accompanying drawings, I have illustrated a form of apparatus for practising the invention, Figure 1 being a vertical section of the combustion chamber and its inclosing jacket, and Fig. 2 a sectional plan 50 on line 2—2 of Fig. 1.

Referring to the drawings, the combustion chamber is preferably formed with a solid or imperforate bottom 2, and a closed top 3 of metal or other refractory material.

55 The chamber here shown is circular with its

side wall 4 formed of an open screen or gauze which is reinforced by a skeleton frame 5, wire mesh, such as copper or other metal being admirably suited for the purpose. Projecting through bottom 2 is a 60 Bunsen burner 6 provided with an air inlet at the exterior of the chamber which is equipped with a suitable regulating valve 7.

8 is the gas inlet pipe, and 9 the valve controlling the gas supply. 65

The burner and valves 7 and 9, together with their adjustments, are of well known construction.

In operation the flame from burner 6 is projected against the center of top plate 3, 70 the latter and the burner being in such proximity and the flame being of such volume that it is prevented from attaining its full normal length. The flame products and unconsumed substances are deflected laterally to the wall-forming copper screen 5, and the cooling effect of top 3 and this screen is such that combustion cannot continue at the exterior of the screen so that the products flowing therethrough pass off unconsumed. It is well known that the flame- 75 inclosed area of an ordinary Bunsen burner, i. e., a burner having a central air supply, consists of at least three zones which extend for a distance outwardly from the burner, 80 all of which zones merge or disappear at the extremity of the flame or inwardly from such point. In that portion of the flame length in which the three zones are defined there is an outside or oxidizing flame-composed zone, an intermediate zone of reduced 85 temperature, and finally a central zone of relatively cold mixed air and gas which has not attained ignition temperature. By interrupting or baffling the flame downwardly 90 or inwardly from its extremity in a plane which intersects these zones the relatively cold substances of the central zone are projected against the top of the combustion chamber which is heated by the flame, and 95 are partially oxidized to formaldehyde, and all of the products, viz., carbon dioxid, water, formic acid, and formaldehyde, pass outwardly through the screen 5. The arrangement is preferably such that the flow 100 or pressure is outward through all portions of the screen, all of the air utilized in the decomposing operation being admitted through the burner.

The combustion chamber is inclosed in the 110

upright jacket 10 provided with air inlets 11, a hood or top 12 and product outlet 13. Openings 11 are preferably in the plane of the lower portion of the combustion chamber and are of such size as to admit an amount of air requisite for efficiently practising the method.

A combustion chamber of the construction shown may not be essential, as conditions 10 requisite for obtaining the desired restricted combustion and the results here desired incident thereto may be secured by different means. Also it will be understood that the products may be collected from their source 15 and separated from each other by various means or processes without departing from the invention.

I make no claim herein to the method or process of producing formaldehyde as the 20 same forms the subject matter of another application filed concurrently herewith.

I claim:—

1. Apparatus for producing formaldehyde comprising a burner for supplying mixed 25 air and gas, means for baffling the substances issuing from the burner and the flame thereof before the substances are fully consumed, and means for confining the flame to a restricted area and for passing the baffled and 30 unconsumed substances away from the flame area.

2. Apparatus for producing formaldehyde comprising a combustion chamber having a closed top which forms a flame and product spreading baffle and with screen-like side 35 walls depending from the baffle for cooling the baffled products passing therethrough and confining the flame within the chamber, and means arranged to project a stream of flame and unconsumed products against the 40 baffle-forming top of the chamber.

3. Apparatus for producing formaldehyde comprising a combustion chamber having a closed top which forms a flame and product spreading baffle, the chamber having a 45 closed bottom and screen-like side walls interposed between the top and bottom, the latter adapted to cool the unconsumed substances and products which are directed therethrough by the baffling action of the 50 chamber top, and a Bunsen burner discharging in the chamber and arranged to project a stream of flame and unconsumed products against the baffle-forming top of the chamber. 55

In testimony whereof I affix my signature in presence of two witnesses.

GUSTAVE FERNEKES.
